UNITED STATES PATENT OFFICE.

CHARLES BELL WOODARD, OF SPRINGFIELD, TENNESSEE.

DEVICE FOR PREVENTING SUCCESSFUL SAFE-BLOWING.

1,146,226.

Specification of Letters Patent. Patented July 13, 1915.

Application filed January 7, 1913. Serial No. 740,635.

To all whom it may concern:

Be it known that I, CHARLES B. WOODARD, citizen of the United States, residing at Springfield, in the county of Robertson and State of Tennessee, have invented certain new and useful Improvements in Devices for Preventing Successful Safe-Blowing, of which the following is a specification.

This invention relates to devices for preventing successful safe blowing, and has as its object to provide a device which may be applied to any ordinary safe and which will act automatically to cause a premature explosion of the nitroglycerin, or other charge introduced at the edges of the safe door so that the burglar attempting to break into the safe will in all probability be so injured as to be unable to escape.

The invention contemplates the provision of a device for the purpose stated which will be automatically actuated by the introduction of a liquid of any type whatsoever at the edges of the door of the safe, so that any liquid explosive having the property of being exploded by percussion will be exploded by the action of a hammer which constitutes an element of the device.

It is one aim of the invention to so mount and actuate the hammer above referred to that it will act repeatedly when the actuating means is released for operation, so as to insure of explosion of the charge.

For a full understanding of the invention reference is to be had to the following description and accompanying drawing, in which:—

Figure 1 is a perspective view illustrating the manner in which the device is arranged within the door of a safe. Fig. 2 is a perspective view illustrating the percussion device. Fig. 3 is a view in elevation of the mechanism, one of the face plates being removed. Fig. 4 is a top plan view of the mechanism. Fig. 5 is a view partly in elevation and partly in section illustrating the mechanism in normal condition. Fig. 6 is a similar view illustrating the positions assumed by the various parts immediately prior to actuation of the percussion device.

Corresponding and like parts are referred to in the following description and indicated in all the views of the accompanying drawing by the same reference characters.

In the drawings the numeral 1 indicates a safe and 2 the door thereof. The edges of the door 2 are stepped in the usual manner

and the stepped portions of the upper side of the door are formed with grooves 3 which lead from the ends of the said portions rearwardly at an angle and communicate with a groove 4 which extends from the uppermost stepped portion to an opening 5 formed vertically in one of the lower stepped portions. At this point it will be apparent that any nitroglycerin introduced at the upper edge of the door 2 will flow into the grooves 3 and be conducted by the grooves 3 to the groove 4 and will finally flow into the opening 5.

The device embodying the present invention is indicated in general in Fig. 1 by the reference character A, and as will be apparent from an inspection of the said figure is disposed within a recess formed in the rear face of the door at a point below the opening 5 in the door.

The device includes in its construction, spaced face plates, one of which is indicated by the numeral 6 and the other by the numeral 7. These face plates 6 and 7 are connected at their corners by means of posts 8 which serve also to space the said plates and it is between these plates that the percussion device and the actuating means therefor are arranged.

Secured upon the inner face of the plate 6 is a percussion-block 9 provided with a bore 10 which slidably receives a percussion pin 11. The block 9 is provided with a funnel-shaped inlet opening 12 which, when the device is in place upon the door of the safe, registers with the lower end of the opening 5. This opening 12 communicates with the bore 10 and the said block is provided with an outlet opening 13 located at that end of the bore opposite the end in which the percussion pin 11 is fitted. A screw 14 is threaded in the under side of the block 9 and engages in a groove 15 formed in the under side of the pin 11 and by coöperating with one end wall of this groove serves to limit the outward sliding movement of the said pin. The pin is normally held by means of a spring 16 disposed between the end of the block 9 and a head 17 at the outer end of the pin, substantially in the position shown in Figs. 3 and 5 of the drawing it being understood that it may be moved inwardly against the tension of the said spring 16 and that when moved its inner end will coöperate with that end wall of the bore in which the opening 13 is

formed. The device also includes a hammer which is arranged to coöperate with the percussion pin 16 and the head of this hammer is indicated by the numeral 18 and is supported at the upper end of a leaf-spring 19 which at its lower end is fixed in a bracket 20 secured upon the face-plate 6. By referring to Figs. 5 and 6 of the drawings it will be apparent that the leaf-spring may be sprung to move the head 18 in a direction away from the percussion-pin and it will be apparent that if after having been so moved, the spring is released, the head 18 of the hammer will strike against the head 17 of the percussion pin thereby sharply forcing the pin against the end-wall of the bore in which it is mounted.

The invention contemplates the provision of means for successively flexing and releasing the hammer spring 19 so as to cause repeated blows to be struck the percussion pin 16, and this hammer actuating means will now be described. A shaft 21 is journaled at one end in the face-plate 7 and adjacent its other end in a bracket 22 which is secured upon the said face-plate, and fixed upon this shaft which rotates therewith is a disk 23 carrying trip-pins 24 which are arranged in a circular series and are equidistantly spaced from each other and from the axis of the said disk. By referring to Fig. 4 of the drawings it will be observed that the pins 24 project in the direction of the face-plate 6 and that the spring 19 of the hammer is located between the disk 23 and face-plate 6 and directly in the path of movement of the pins 24. The said leaf-spring has its edge which is presented toward the disk 23, cutaway as at 25 so as to clear the pins 24 at times and under conditions to be presently explained. While the disk 23 is illustrated as provided with a set of four pins a greater or less number may be employed, if found desirable, and in order that the number of pins may be readily varied, the disk is formed with openings 26 into which the pins are removably and interchangeably fitted. It will now be apparent that as the disk 23 is rotated, the pins 24 are successively swept over the upper portion of the leaf-spring 19 until they reach the upper end of the cutaway portion 25 thereof, whereupon the leaf-spring may be released and the hammer head 18 will be caused to successively strike the headed end of the percussion pin. It will also be seen that the frequency with which the spring is flexed and released depends upon the speed of rotation of the disk 23 and upon the number of pins carried by the disk.

As will be presently explained, the disk 23 is driven by suitable spring-motor means and in order that the mechanism as a whole may be restrained against operation, under normal conditions, there is provided a de-

tent device which is clearly shown in Figs. 2, 5 and 6 of the drawing. This device includes a rock-member 27 having a finger 28 which projects beside the face of the disk 23, and a finger 29 projects upwardly from the pivot for the rock-member, which pivot is indicated at 30. A plate 31 is secured upon the inner face of the face-plate 6 and has a laterally projecting portion 32 located opposite the upper end of the finger 29. A spring 33 is coiled about the pivot 30 and has one end engaging behind the finger 28 and the other end engaging behind the laterally projecting portion 32 of the plate 31. This spring by reason of its arrangement, tends to move the finger 29 in the direction of the said plate 31. Disposed between the upper end of the finger 29 and the laterally projecting portion 32 of the plate 31, is a disintegrable element 34 which is preferably in the nature of a block of chalk although any other material which will disintegrate under the action of moisture may be found suitable for use. It will be observed from inspection of Figs. 3 and 5 of the drawings that the end of the block in which the opening 13 is formed, is provided with a channel 35 leading downwardly from the said opening, and it will be apparent that the lower end of this channel is located directly above the disintegrable element 34 so that any nitroglycerin or other explosive liquid introduced at the top of the safe door and flowing into the bore of the percussion-block and out through the opening 13 will saturate the disintegrable element 34 and cause its disintegration. It will also be apparent by reference to Fig. 5 that under normal conditions the rock-member 27 is held by the disintegrable element 34 in such position that the end of its finger 28 will be in the path of movement of the pins 24 and consequently the disk 23 will be restrained against rotative movement. It will be understood, however, that upon disintegration of the element 34 and the release of the rocker 27 the spring 33 will move the latter to the position shown in Fig. 6 thereby releasing the disk 23 for rotative movement under the action of the spring motor driving means, heretofore referred to and which will now be fully described.

A gear 36 is fixed upon the shaft 21 and meshes with a pinion 37 upon a shaft 38 mounted in a bracket 39 upon the face-plate 7. The shaft 38 also carries a gear 40 which is in mesh with a pinion 41 upon a shaft 42 mounted in a bracket 43 upon the said face-plate. A gear 44 is fixed upon the shaft 42 and meshes with a pinion 45 upon a governor shaft 46. This governor shaft has fixed upon it one head 47 of a centrifugal governor 48, the other head indicated at 49 being slidable upon the shaft and being fixed for rotation with a friction disk 50. A bracket

is fixed upon the face-plate 6 and has a pair of arms 51 which project toward the disk 50 and support at their outer ends sleeves 52 which are located at diametrically opposite 5 points with relation to the shaft 46. Threaded within each of the sleeves 52 is a stem 53 carrying a friction foot 54 designed to co-operate with the face of the friction disk 50 whereby to retard the speed of rotation 10 of the same. It will be understood, of course, that by rotating the stems 53 the friction feet 54 may be adjusted with relation to the friction disk. The gear 36 is in mesh with a pinion 55 which in turn meshes 15 with a gear 56 which is fixed for rotation upon a shaft 57 mounted in a bracket 58 upon the face-plate 7. The shaft 57 carries a pinion 59 which meshes with a gear 60 upon a power-shaft 61 to which is connected 20 one end of the motor-spring 62, the other end of this spring being secured as at 63 at one end of an arcuate shield 64 arranged between the face-plates 6 and 7. One end of the shaft 61 projects through the face-plate 25 7 and is squared as at 65 for the engagement therewith of a suitable winding key (not shown). The gear 60 is clutched with the shaft 61 by the usual arrangement of pawls and ratchets 66.

30 From the foregoing description of the invention it will be apparent that after the device has been wound and the disintegrable element 34 has been disposed between the member 32 and the end of the finger 29, and 35 the whole has been arranged within the recess in the safe door, it is ready for actuation and requires no further attention. Should one attempting to gain access to the safe pour a quantity of nitroglycerin or 40 other liquid explosive into the crack between the upper edge of the safe door and the upper wall of the door opening, this liquid would be conveyed by way of the grooves in the upper edge of the door to the opening 45 5 and would flow into the percussion block and through the opening 14 and onto the disintegrable element 34. This element, as soon as it becomes saturated, will disintegrate thereby releasing the rocking member 50 27 and incidentally releasing the disk 23 for rotative movement. As will be apparent from the foregoing, this disk will be set in motion by the spring-motor mechanism and as it rotates the hammer will be successively 55 actuated to strike blows against the headed end of the percussion-pin 16. While it is natural to suppose that the first blow struck the pin will serve to explode the charge introduced into the safe, it will be evident 60 that should the first blow fail to accomplish this result the blows subsequently given will serve to explode the charge.

65 It will be noted that the door is provided, in addition to the grooves 3 and 4, with grooves 3^a which are formed in the side

edges of the door, and these grooves serve to conduct the explosive to the grooves 3 and 4 in the event that the safe is laid upon its side and the explosive charge is introduced at the side of the door instead of at the top. 70 It will be understood, of course, that the grooves may be continued entirely around the door.

Having thus described the invention what is claimed as new is:—

1. In a device of the class described, a percussion device having a liquid inlet and a liquid outlet, a hammer arranged to co-operate with an element of the percussion device, means for actuating the hammer, and means 80 normally restraining the hammer actuating means located adjacent the liquid outlet and arranged to be rendered inoperative when subjected to moisture.

2. In a device of the class described, a percussion device having a liquid inlet and a liquid outlet, means for actuating the percussion device, and means located adjacent the liquid outlet and normally restraining the actuating means arranged to be rendered 90 inoperative when subjected to moisture.

3. The combination with a safe, or the like, of percussion means arranged therein, for the explosion of an explosive charge, introduced into the safe, said means operated by contact of the charge with an element of the means.

4. In a device of the class described, a percussion element, a hammer arranged to co-operate therewith, means for intermittently actuating the hammer, and means normally restraining the hammer actuating means and including an element having the property of 100 disintegrating when subjected to moisture.

5. In a device of the class described, a percussion element, a hammer arranged to co-operate therewith, a spring for actuating the hammer, means for intermittently tensioning and releasing the spring, and means normally restraining the last mentioned 110 means against movement and including an element having the property of disintegrating when subjected to moisture.

6. In a device of the class described, a percussion element, a leaf-spring, a hammer head carried by the leaf-spring and arranged for co-operation with the percussion element, a rotary trip member arranged for co-operation with the leaf-spring to flex and release the same, and means normally restraining 115 the trip member from operation including an element having the property of disintegrating when subjected to moisture.

7. In a device of the class described, a percussion element, a leaf-spring, a hammer head carried by the leaf-spring, a rotatable trip disk, a series of trip pins carried by the disk and arranged to successively engage with the leaf-spring and upon rotation of the disk to flex and release the same whereby 120 125 130

to cause successive engagement of the hammer with the percussion element, means for rotating the disk, and means normally holding the disk against rotation and including 5 an element having the property of disintegrating when subjected to moisture.

8. In a device of the class described, a percussion element, a leaf-spring, a hammer-head carried by the leaf-spring and arranged 10 to coöperate with the percussion element, a rotatable disk, means for rotating the disk, a series of trip-pins carried by the disk and adjustable as to their position upon the disk, the said trip-pins being arranged upon rotation of the disk to successively engage with 15 the leaf-spring and flex and release the same whereby to cause successive coöperation of the hammer-head with the percussion element, means normally engaged with one of 20 the pins and restraining the disk from rotative movement, the said means being movable out of engagement with the pin, and an element normally holding the said means in engagement with the pin and having the 25 property of disintegrating when subjected to moisture.

9. In a device of the class described, a percussion element, a hammer arranged to coöperate with the percussion element, a trip 30 member arranged to actuate the hammer, a rock-member having a finger engageable with an element of the trip member whereby to hold the trip against movement, means tending to move the rock-member out of position for such engagement, and an element 35 for holding the rock-member in position for such engagement and having the property of disintegrating when subjected to moisture.

10. In a device of the class described, a

percussion device including a block having 40 a bore and inlet and outlet openings in communication therewith, a percussion-pin mounted for movement in the bore and arranged to coöperate with one end wall of the bore, a hammer arranged for coöperation 45 with the percussion pin, means for actuating the hammer, and means normally restraining the actuating means from operation including an element positioned beneath the outlet opening from the bore and having 50 the property of disintegrating when subjected to moisture.

11. In a device of the class described, the combination with a safe, the door of which is provided with a recess and with an opening 55 in communication with the recess and in its edges or steps with grooves leading to and in communication with the opening, of means arranged within the recess for exploding an explosive charge introduced into the safe 60 and flowing through said grooves to said opening, said means including a percussion element, a hammer arranged for coöperation therewith, means for actuating the hammer, and means normally restraining the actuating 65 means from operation and including an element having the property of disintegrating when subjected to moisture, the said element being arranged in juxtaposition to the opening whereby to be acted upon by the explosive charge.

In testimony whereof I affix my signature in presence of two witnesses.
